(57) **CLAIM**

The ornamental design for a water meter, as shown and described.

DESCRIPTION

1. Water meter

1.1 : Perspective

1.2 : Front

1.3 : Left

1.4 : Top

1.5 : Bottom

The left side view is a mirror image of the right side view; the front view is a mirror image of the rear view; broken lines illustrate environmental structure and form no part of the design.
